US0D1016228S

(12) **United States Design Patent** (10) Patent No.: **US D1,016,228 S**
(45) Date of Patent: ** Feb. 27, 2024

(54) **FAUCET**

(71) Applicant: **HANSGROHE SE**, Schiltach (DE)

(72) Inventors: **Andreas Diefenbach**,
Ludwigsburg-Ossweil (DE); **Philip
Heinrich**, Stuttgart (DE)

(73) Assignee: **Hansgrohe SE**, Schiltach (DE)

(**) Term: **15 Years**

(21) Appl. No.: **29/831,389**

(22) Filed: **Mar. 18, 2022**

(30) **Foreign Application Priority Data**

Sep. 27, 2021 (EM) 008707889-0011

(51) LOC (14) Cl. **23-01**

(52) U.S. Cl.

USPC **D23/238**

(58) **Field of Classification Search**

USPC D23/238-244, 252, 254-255, 257, 499;
D7/398

CPC F16K 31/602; F16K 31/605; F16K 31/607;
E03C 1/0412

(57) **CLAIM**

The ornamental design for a faucet, as shown and described.

DESCRIPTION

FIG. 1 is a perspective view of a faucet showing our design;

FIG. 2 is a front elevational view;

FIG. 3 is a rear elevational view;

FIG. 4 is a side elevational view;

FIG. 5 is a side elevational view;

FIG. 6 is a top plan view; and,

FIG. 7 is a bottom plan view.

The broken lines are included for the purpose of illustrating portions of the faucet that form no part of the claimed design.

1 Claim, 7 Drawing Sheets
